Atty.

UNITED STATES PATENT OFFICE

ANTHONY HLAVAC, OF CHICAGO, ILLINOIS, ASSIGNOR TO EBER J. HUBBARD, OF BERWYN, ILLINOIS

COP HOLDER

Application filed April 24, 1929. Serial No. 357,756.

My invention relates to cop holders for supporting cops of yarn or thread to be fed, for example, in braiding machines.

The important object of the invention is to provide a more efficient form of supporting base and more efficient means for rigidly securing a spindle tube to the base against rotational or longitudinal displacement.

The above features and others are incorporated in the structure shown in the drawings in which

Fig. 1 is a side elevation,

Fig. 2 is a plan view,

Fig. 3 is a bottom view,

15 Fig. 4 is a section on line 4—4, Fig. 1,

Fig. 5 is a plan view of the base,

Fig. 6 is a side elevation of the lower end of the spindle tube, and

Fig. 7 is an end view of the spindle tube.

20 The base 10 is cylindrical and may be a die casting of aluminum or other light and tenacious metal. On its under side the base has the radial ratchet teeth 11 extending from the hub 12 to the base periphery. The front 25 faces 13 of the teeth are in vertical planes and the backs 14 are gradually inclined or bevelled, while the crowns 15 are of sufficient width to form with the hub end adequate seating surface for the base. The hub 30 has the axial cylindrical opening 16 for receiving the spindle tube 17 and on its top has the collar or flange 18 one of whose purposes is to increase the length of the opening 16 and consequently the seating surface for the 35 spindle tube.

Extending radially into the opening 16 the full length of the hub and the collar is the spline or abutment 19 whose inner surface 20 is concentric with the opening and whose 40 radial depth is equal to the thickness of the sheet metal from which the spindle tube is formed. The hub at its lower end is countersunk or recessed to a depth equal preferably to the thickness of the spindle tube metal to 45 form the shoulder 21 which does not entirely surround the opening 16 but is interrupted by the hub part 22 whose radial sides 23 and 24 are in the planes of the radial sides 25 and 26 of the spline 19. In other words, the part 50 22 forms a spline in the recess space below

the shoulder 21 and is a continuation of the spline 19 in the opening 16.

The spindle tube 17 is formed by bending a sheet of metal into cylindrical form with the longitudinal edges abutting as shown 55 at 27 in Fig. 6. At its lower end the tube has the longitudinal slot 28 whose width is equal to the distance between the spline side surfaces 25 and 26, and the tube is of outer diameter to fit snugly in the base opening 16. 60 When the tube is inserted in the opening the sides *a* of its slot abut against the spline sides 25 and 26 and the upper edge *b* of the slot seats against the top of the spline 19. The slot is longer than the opening 16 so that 65 the lower end of the tube will extend below the opening to be deflected radially into the hub countersunk space and against the shoulder 21 to form a locking flange 29 whose ends abut against the spline surfaces 23 and 24. 70 Such engagement of the tube with the spline surfaces locks it rigidly to the base against rotational displacement, and the clamping of the base axially between the upper edge *b* of the slot 28 and the flange 29 rigidly secures 75 the tube against longitudinal displacement. The long continuous opening 16 and corresponding extensive engagement between the base and tube greatly adds to the strength and rigidity of the joint.

As shown (Fig. 6) the line of the tube seam 27 is between the sides of the slot 28 so that when the tube is secured in the base the seam edges will be held against relative longitudinal displacement and the tube strengthened 80 against twisting.

As the shoulder 21 is of a depth equal to the thickness of the spindle tube metal, its outer face will be in the plane of the hub end and teeth crowns and will afford additional bearing surface for the base on its support.

85 Cops usually have paper cores on which the yarn or thread is wound. To center the cap on the spindle tube and to hold it against rotation thereon I provide the frame 30 formed from a single piece of sheet metal and comprising the upper and lower sleeves 31 and 32 connected by longitudinal springy ribs 33 which ribs may be of substantially 90 semicircular cross section. The sleeves inti- 100

mately fit the spindle tube and are secured thereto preferably by spot welding, the upper sleeve 31 ending flush with the upper end of the spindle tube and the lower sleeve 32 seating against the top of the base collar 18 and assisting in locking the spindle tube against longitudinal displacement on the base. The ribs 33 will depress into the cap core and lock the cap against rotational movement on the holder, and the collar 18 will receive the lower end of the core and will center the cap on the base, the collar upper edge being bevelled as indicated at 34 so that the cap core can more readily receive the collar. The base being of light metal such as aluminum can be of substantial volume without unduly increasing the weight, and it therefore permits of the long seating opening for the spindle tube so that the tube can be rigidly secured and held against displacement under heavy work and load, and the holder will resist the wear and tear incidental to its use. The spindle tube being of steel, its lower end will form a resistant bearing lining for the base, and the flange 29 will resist wear of the base bottom particularly adjacent to the spindle on which the holder is mounted.

I do not desire to be limited to the exact structure shown as modifications may be made without departing from the scope of the invention.

I claim:

1. A cop holder comprising a base having a long continuous axial opening, a metallic spindle tube snugly fitting at its lower end in said opening, and a spline on said base extending full length of said opening and being of a radial depth equal to the thickness of the spindle tube metal, said tube having a slot receiving said spline whereby it is locked to the base against rotational displacement, the tube at the upper end of its slot resting against the top of the spline and the lower end of said tube being deflected radially and against the base bottom whereby said tube is locked against longitudinal displacement.

2. A cop holder comprising a base having a long continuous axial opening and having a recess in its under side surrounding said opening, a spline on said base extending full length of said opening and into said recess, and a metallic spindle tube snugly fitting in said opening and having a slot receiving said spline whereby it is locked against rotational displacement, said tube at the upper end of its slot resting against the upper end of said spline and the tube at the lower end of said slot being deflected into said recess whereby the tube is locked against longitudinal displacement.

3: A cop holder comprising an integral base having a long continuous axial opening and having a recess in its under side surrounding said opening, a collar on the upper

side of said base-surrounding and prolonging said opening, a spline on said base extending full length of said opening and into said recess, and a metallic spindle tube fitting at its lower end in said opening and having a slot receiving said spline whereby it is locked against rotational displacement, the tube at the upper end of its slot resting on top of said spline and the tube metal around the lower end of the slot being deflected into said recess whereby said tube is clamped against longitudinal displacement.

4. A cop holder comprising a solid metallic base having a long axial opening and a recess in its under side surrounding said opening, a collar on the upper side of said base surrounding and prolonging said opening, a spline on said base extending into said opening and said recess, a metallic spindle tube slotted at its lower end to receive said spline and being deflected into said recess, and a cop clamping frame on said spindle tube and seating on said collar.

In witness whereof, I hereunto subscribe my name this 23d day of April, 1929.

ANTHONY HLAVAC.
